WIRE TWISTER

Original Filed Dec. 26, 1924

2 Sheets-Sheet 2

UNITED STATES PATENT OFFICE.

MARCIAN E. SAUNIER, OF BAY CITY, MICHIGAN.

WIRE TWISTER.

Continuation of application Serial No. 758,066, filed December 26, 1924. This application filed December 24, 1925. Serial No. 77,450.

This invention relates to wire twisters and the like, and is a continuation of my application for Letters Patent for wire twisters filed December 26, 1924, Serial No. 758,066.

5 One object of the invention is to provide a simple and efficient wire twister for use in twisting the form wire on construction forms and other concrete form work.

Another object is to provide a simple and inexpensive tool for 10 stretching the wire taut, and then twisting the ends thereof to hold the forms securely in place.

A further object is to provide a tool by 15 means of which the form wires can be stretched and twisted from the outside of the forms, eliminating the necessity of the workman crawling into the space between the forms, and twisting the wire tight with 20 a short stick, or other suitable implement.

A still further object is to design a wire twister provided with release mechanism to allow the tool to quickly and easily release the wire.

25 A further object still is to provide a tool for use in twisting the wire on packing boxes.

The above and other objects will appear as the specification progresses, reference being had to the accompanying drawings in which like reference numerals indicate like parts throughout the several views thereof.

In the drawings—

Fig. 1 is a side view of my improved wire twister.

35 Fig. 2 is a front view thereof.

Fig. 3 is an enlarged part sectional side view of the head and jaws, the release mechanism being shown in two different positions.

40 Fig. 4 is a top plan view of the mechanism shown in Fig. 3.

Fig. 5 is a detail side view of the revolving head.

45 Fig. 6 is a side view of the set of jaws.

Fig. 7 is an edge view thereof, and

Fig. 8 is a sectional view of one of the toothed jaws.

50 Fig. 9 is an isometric view of a form for a building column and showing the tool in position for twisting the wire.

In the ordinary labor of erecting forms for retaining walls, foundation walls, columns, and in fact forms of any nature into

which concrete is poured, it is customary 55 to provide spaced apart wire or rods, either threaded or clamped by various external devices to prevent the forms spreading due to the weight of the concrete. This is usually done by drilling holes through the form 60 lumber on either side of one of the vertical studs and passing a strand of wire therethrough, bringing the ends together and twisting with a pair of pliers to make the wires taut. It is then necessary for the 65 workman to get into the space between the forms, and with a hammer handle or other implement, twist the strands of wire until the required tension is secured; oftentimes 70 the space is so narrow that it is extremely difficult to crowd into, and the work is necessarily slow and tedious.

My improved wire twister eliminates these 75 objectionable features, and enables the form wires to be quickly and easily twisted to proper tension from the outside of the form or column. It further permits of the quick and easy displacement and removal of the usual spacer members which are inserted 80 directly adjacent each wire in wall form work, thereby eliminating the necessity of additional wires which ordinarily remain in place until the concrete is set.

Referring now particularly to the drawings in which I have shown the preferred 85 embodiment of my invention, the numeral 1 indicates a hollow tubular barrel or casing, having an offset downwardly projecting leg or portion 2 formed integral therewith, the end of which terminates in a curved shoe 3 90 adapted to engage one edge of the vertical studding, column or the material of which the form or box is constructed.

A shaft 4 extends through and is revolvably mounted in this tubular barrel 1, a crank 95 member 5 being pinned, keyed or otherwise secured to the upper end thereof, and a laterally projecting handle 5^a is secured to the opposite end of the crank in any approved manner to facilitate the turning thereof.

The opposite end of the shaft 4 is threaded, projects beyond the casing, and is adapted to be introduced into a threaded opening 4^a provided in the head 6, and which is locked in position by means of a transversely disposed key 6^a which extends therethrough. Oppositely disposed lugs 7 and 8 are cast 105 integral with and project from opposite sides

of the head and the wire gripping mechanism is secured thereto in a manner to be presently described.

Another offset lug 9 is formed integral with the head and at the lower end thereof, and a pair of spaced apart jaw members 10 are pivotally secured thereto by means of a pin member 11, said jaws being formed as clearly shown in Figs. 6 and 7 of the drawings, and straddle the lug member 7, a rib or side wall 12 being formed on the outer edge of each jaw, and prevents displacement of the wire.

A pair of individual cam shaped jaws 13 are pivotally secured to the opposite lug 8 by means of the pin 14, the face or jaw having small teeth which cooperate with the jaws 10 for gripping the wire and preventing slippage thereof, cotter pins 15 being inserted through the pins to prevent displacement of the wire.

The pivoted jaws 10 are held in position by means of spaced apart cam shaped lugs 16 mounted on a pin 17 which is journaled in the member 7, a release lever 18 being cast integral with said lug members to facilitate the release of said jaws when it is desired to release the tool from the wire. A flat resilient spring member 19 is secured to the 30 forked jaw 10 by means of screws 20, and are forked as shown, the upper ends engaging the cam shaped lugs 16 to hold them in proper position.

In practice the form wire is threaded 35 through the forms or placed in position around a column form, the ends projecting as shown, the ends of the wire are then crossed and placed in each respective jaw, and the shoe 3 placed in position against one 40 of the vertically disposed stud members or the corner of the column or box, a prying action is then exerted by the operator in the direction as indicated by the arrow B, pulling the wires taut and the crank 5 is then 45 rotated and the wire twisted until the desired tension is secured, the release lever 18 is then swung to position as indicated in dotted lines in Fig. 3, releasing the jaws 10 and allowing them to rock on the pivot and 50 release the wire when the tool can be quickly and easily removed.

It will of course be obvious that increased leverage on the outer end of the barrel pulls the wires taut and serves to more tightly 55 clamp the wire between the jaws, and that releasing mechanism must be provided, otherwise it would be very difficult to disengage the tool, as the twists would extend to and be tight against the head proper and no play would be afforded.

The fact that the twisting is accomplished outside of the forms facilitates the inserting of a suitable tool between the wire strands for displacing the spacers (not shown) and removing them from the form.

From the foregoing description it will be obvious that I have perfected a very substantial, simple and economical wire twister.

What I claim is:—

1. A tool of the character described comprising a barrel having an offset shoe rigid thereon and projecting beyond the barrel, a rotatable head journaled in the barrel, jaws pivotally mounted on the head, and means for revolving said head. 75

2. A tool of the character described comprising a barrel having an offset leg formed with a shoe, a head rotatably journaled in the barrel, pivoted jaws mounted thereon in pairs, releasable means for limiting the 80 movement of one set of jaws, and means for revolving said head.

3. A tool of the character described comprising a barrel having an offset shoe, a head journaled thereon, spaced apart jaws pivotally mounted thereon in pairs, a release lever pivotally secured to said head and having a cam shaped head, resilient means mounted on the jaws for holding one set of jaws in predetermined position, and manually operable means for revolving said head. 90

4. A tool of the character described comprising a tubular barrel having an offset downwardly projecting leg, a shaft in the barrel, a head mounted thereon, jaws pivotally mounted thereon in pairs, means for limiting the travel of one set of jaws, and comprising a release lever pivotally secured to the head and having a cam shaped end, and resilient means on the jaws and engaging said cam shaped end for holding the lever in adjusted position, and means for rotating said head. 95

5. In a device of the character described comprising a barrel having an offset downwardly projecting lug portion terminating in a shoe, a shaft mounted in said barrel, a head secured thereon, spaced apart jaws pivotally mounted thereon in pairs, a release lever pivotally mounted on the head and formed with a cam shaped head adapted to engage one set of jaws, and a lever formed integral therewith adapted to be manipulated to release said jaws, and a crank on the shaft for rotating said head. 105

6. In a device of the character described comprising a barrel having a downwardly projecting offset leg terminating in a shoe, a shaft journaled in said barrel, a head detachably secured thereto and having offset lugs, spaced apart jaws pivotally mounted on said lugs in pairs, means for holding one set of jaws in predetermined position, and including a release lever having a cam shaped head adapted to be actuated to release one set of jaws and allow for a limited movement thereof, and a crank secured on the shaft for revolving the head. 110

7. A tool of the character described comprising a stationary barrel having an offset 115

leg formed with a shoe integral therewith and projecting beyond the end of the barrel, a head rotatably journaled in the barrel, cam shaped jaws pivotally mounted thereon, and a crank on the opposite end of the head.

8. A tool of the character described comprising a stationary barrel having an offset leg formed with a shoe and projecting beyond the end of the barrel, a shaft revolvably

mounted in said barrel, a crank on one end thereof, a head mounted on one end of the shaft, and comprising jaws pivotally mounted thereon and adapted to grip a wire, and a crank on the opposite end for revolving said head.

In testimony whereof I affix my signature.

MARCIAN E. SAUNIER.
